UNITED STATES PATENT OFFICE.

CHARLES D. KING, OF RUTHERFORD, NEW JERSEY.

PNEUMATIC PISTOL AND GUN.

Application filed April 15, 1921, Serial No. 461,517. Renewed June 3, 1925.

To all whom it may concern:

Be it known that I, CHARLES D. KING, a citizen of the United States, residing at Rutherford, in the county of Bergen and 5 State of New Jersey, have invented certain new and useful Improvements in Pneumatic Pistols and Guns, of which the following is a specification.

This invention relates to pneumatic pistols and guns, and its main object is to provide an improved device of this type embodying means whereby a piece of paper clamped across an aperture formed in a portion of the device, can be suddenly 15 broken by compressed air, causing a loud report similar to that of a firearm. The invention relates especially to means for holding the paper, and also to the means of applying pneumatic pressure, together with 20 the devices for bringing the pneumatic pressure suddenly into operation.

The means I prefer to employ for accomplishing the above object, together with other features of my invention, are illustrated in the drawing accompanying and 25 forming part of this specification, and in which—

Figure 1 is a longitudinal section of my improved pneumatic pistol or gun in its 30 preferred form and in the set position thereof.

Fig. 2 is a side elevation of the same, and Fig. 3 is a front end elevation of the same.

Like characters of reference refer to like 35 parts in all the figures of the drawings.

In the various figures of the drawings the numeral 2 designates a suitable plunger chamber, 3 designates the barrel, and 4 a spring chamber which may be made in any 40 suitable manner such as formed within the barrel as shown in Fig. 1. The plunger chamber may be formed in any suitable way, as for instance it may be cast, machined or otherwise formed in a casing 5, and the 45 barrel may be secured thereto in any suitable manner as by means of screws 6.

Any suitable means may be provided to hold the device when in use, such as the pistol grip or handle 7 formed of sheet metal 50 and secured to the casing by suitable means such as rivets 8.

In the plunger chamber 2 is provided a plunger 9 which may be of any suitable form and preferably has a foot 10 on which 55 it slides along the bottom of the plunger chamber. A plunger rod 11 is connected to

the plunger 9 by suitable means such as by passing it through a hole 12 in an extension 13 of the plunger and securing it by means of a pin 14 as illustrated in Fig. 1. The said extension 13 extends through a slot 15 to bring it to the level of the rod 11. The plunger rod 11 passes through a hole in the partition 16 in the barrel, and is provided with a disk 17 at the forward end. A suitable spring such as 18 is held in the spring chamber 4, and when said spring is compressed by pulling back on the handle 19 on the disk 17 and movable in the slot 20, the plunger is also pushed back by means of its 60 rod 11, and can be caught by suitable let-off or trigger mechanism such as 23. The said mechanism embodies a latch portion 24 adapted to engage a projection 25 on the rear part of the plunger. A trigger 26 is 65 formed integral with the latch and is normally pressed against a pin 27 by means of a spring 28 secured in a recess 29 in the casing 5.

In the forward end of the plunger chamber 2 is a threaded aperture 32 in which is clamped a rubber member 33 by means of a nut 34. The said nut 34 holds the member 33 by its flange or skirt 35, against the rear portion or shoulder of said aperture and is 70 provided with holes 36 by means of which it can be turned into place by means of a spanner or wrench. A coil spring such as 37 may be employed to keep the member 33 distended. The said member is compressible and when its rounded wall 38 is pressed 75 forward, it acts as a diaphragm to compress the air in the space 39 between said wall 38 and the paper C.

Hinged to a suitable support, such as the 80 forward part of the casing 5, is a clamping member 40, having a hole 41, a handle 42, and ears 43, through which the hinge pin 44 passes and secures it to the forward part of the casing 5. A rubber ring 47 is fastened 85 in a seat 48 so that the ring may clamp a paper C against the face of the nut 34. A spring catch 49 is secured by screws 52 to the casing 5 and is provided with a projection 51 adapted to engage the lower edge of 90 the member 40 when said member is pressed against the nut 34, and holds the paper 95 firmly clamped.

When the paper C is thus held clamped, the plunger 9 can be set by pulling back on 100 the handle 19 until the projection 25 is caught by the latch 24. On pulling the trig-

ger 26, the plunger 9 is released and the spring 18 drives it against the compressible wall 38 of the member 33 which in turn moves towards the paper C compressing the air in the space 39 until the paper gives way with a loud report.

It is evident that the mere mechanism for giving the several movements to the different parts may be modified or changed in various ways and any suitable form of parts may be employed without departing from the spirit and principle of the invention and I do not therefore confine myself to the details of construction here shown.

15. What I claim is:

1. In a device of the class described, the combination of a portion embodying a plunger chamber, a plunger movable therein, means to clamp a film across an end of said chamber, a spring to move the plunger in the direction of the film, a rubber diaphragm located in the chamber between the plunger and the film, a holding ring for said diaphragm, and a coil spring between 25 the diaphragm and said ring to distend the former.

2. The combination of a frame having a plunger chamber, a plunger adapted to be moved backward and forward in said chamber, a barrel having an axis eccentric to that of the plunger chamber and an opening at the rear communicating with the plunger chamber, a spring-rod in said barrel and connected to said plunger, a spring in said barrel to move said rod and plunger, film-holding means at the end of said plunger chamber, and let-off mechanism for said plunger.

3. The combination of a frame having a plunger chamber and a slot over said chamber, a barrel over said chamber, a plunger having an extension movable in said slot, a spring held in said barrel, a spring-rod connected to said plunger extension and to said spring, film-holding means at the end of said plunger chamber, and let-off mechanism for said plunger.

4. The combination with a frame embodying a plunger-chamber having an internally-threaded, annular recess at one end, a plunger, a plunger-spring, and trigger mechanism, of a diaphragm near the end of said chamber provided with a skirt extending into said recess, a ring-nut to secure said skirt, a member having an opening therethrough and hinged at the end of said chamber, and means to compress and hold said hinged member against said ring-nut.

5. The combination with a plunger, a plunger-spring, a frame having a plunger chamber, a diaphragm near the end of said chamber, and let-off mechanism for said plunger and spring, of a film holder which includes a member hinged at one side, having a hole in line with the plunger, and an annular recess in the side next to the plunger.

er, an elastic ring attached to the hinged member in said recess, and catch mechanism whereby the elastic ring can be compressed and held against a film at the end of the plunger chamber.

6. The combination of a frame embodying a plunger chamber, a plunger in said chamber, a barrel over said chamber, a plunger spring in said barrel suitably connected, a diaphragm having a skirt near the end of the plunger chamber, means to clamp the skirt of the diaphragm in such position, trigger mechanism for said plunger, and film-holding means for the diaphragm end of the plunger chamber which include an apertured member having an annular recess on the film side, an elastic rubber ring in said recess, means to hinge the apertured member to the casing of the barrel and chamber, and a spring-latch to hold the apertured member in position compressing said rubber ring.

7. The combination of a frame having a plunger chamber, film-holding means at one end of the plunger chamber, a barrel over the plunger chamber and having a longitudinal slot and an opening in the rear lower part communicating with the plunger chamber, a plunger adapted to be moved backward and forward in the plunger chamber, a spring-rod in said barrel and connected to the plunger, a spring in said barrel to move said rod and plunger whereby the latter is moved toward the film-holding means, a handle secured to said rod and projecting through and movable in said slot for setting the spring-rod and plunger, and let-off mechanism for said plunger.

8. The combination of a frame having a plunger chamber, film-holding means at one end of the plunger chamber, a barrel over the plunger chamber and having an opening in the rear lower part communicating with the plunger chamber, a plunger adapted to be moved backward and forward in the plunger chamber, a spring in the barrel to move said plunger towards the film-holding means, trigger mechanism for the plunger, and means to move the plunger into set relation thereto.

9. The combination of a member having a plunger chamber, film-holding means at one end thereof, and a plunger in said chamber adapted to be moved back and forth therein and to be moved suddenly to juxtaposition to the film and means for guiding the plunger which means are substantially parallel with and exterior to the plunger chamber and on a different axis.

10. The combination of a member embodying a plunger chamber, a plunger in said chamber, film-holding means at one end of said chamber, a spring located above the plunger chamber exterior to and substantially parallel therewith and on a different axis.

axis, and connected to the plunger for moving it toward the film-holding means, trigger mechanism for the plunger, and means to move the latter into set relation thereto.

5 11. The combination with a member embodying a plunger chamber having an annular recess at one end distinct from the main bore of the chamber, film-holding means at said end of the plunger chamber, a 10 plunger in said chamber, means to move the plunger back and forth in said chamber including means to move it suddenly toward the film-holding means, and trigger mechanism for said plunger, of a diaphragm 15 having a holding portion in said recess and an annular member separate from the film-holding means, to secure said holding portion in said recess.

12. The combination with a member embodying a plunger chamber, a plunger in 20 said chamber, a diaphragm at one end of the plunger chamber, means to move the plunger to and fro in said chamber including means to move it suddenly toward the diaphragm, and trigger mechanism for said 25 plunger, of film-holding means which include an aperture oscillating member having an annular recess and adapted to be held at said end of the plunger chamber and a resilient ring separate from the dia- 30 phragm, carried by said apertured member in said recess and adapted to clamp the film.

Signed at New York, in the county of New York, and State of New York, this 12th day of April, 1921.

CHARLES D. KING.
